PETTER C. N. PEDERSON, OF SUPERIOR, WISCONSIN.

FLOOR-COVERING.

1,128,182.

Specification of Letters Patent.

Patented Feb. 9, 1915.

Application filed November 8, 1913. Serial No. 799,979.

To all whom it may concern:

Be it known that I, PETTER C. N. PEDERSON, a citizen of the United States, residing at Superior, in the county of Douglas and State of Wisconsin, have invented a new and useful Floor-Covering, of which the following is a specification.

This invention has reference to improvements in floor coverings, and is designed to provide a substantially permanent floor covering producing a smooth unbroken surface particularly resistant to wear, and which is susceptible of preparation in various ways.

In accordance with the present invention paper constitutes the principal ingredient of the floor covering and the invention contemplates the preparation of the floor for the reception of paper layers which afterward, or even in some instances before application to the floor, may be suitably protected or decorated where exposed to sight and wear.

The invention will be best understood from a consideration of the following detailed description, taken in connection with the accompanying drawings forming a part of this specification, with the further understanding that while the drawings show a practical form of the invention, the latter is not confined to any strict conformity with the showing of the drawings and may be changed and modified so long as such changes and modifications mark no material departure from the salient features of the invention.

In the drawings:—Figure 1 is a perspective view with parts broken away illustrating the various steps in the preparation of the floor and the application of the floor covering, the proportions being greatly exaggerated in the illustration. Fig. 2 is a perspective view of an overlapping joint between two pieces of paper used in the floor covering. Fig. 3 is a perspective view showing a floor covering prepared as in Fig. 1 with a superimposed covering of similar construction. Fig. 4 is a perspective view showing another type of superimposed floor covering. Fig. 5 is a perspective view showing a somewhat different arrangement than in the other figures. Fig. 6 is a fragmentary perspective view of an arrangement which may be employed in conjunction with the joints of the under paper layer.

Referring to the drawing there is indicated a small portion of a floor 1 which may

be taken as indicative of any flooring, which it is desired to cover, whether of wood or concrete or the like. Such floor, which may be relatively rough, is first sized with flour 60 paste, indicated at 2, or other substances such as glue, varnish, paint, soap and the like may be employed, especially on old floors which have been variously pretreated, and then to this sized flooring is applied a 65 layer 3 of plaster of Paris, or any other suitable substance for the purpose, the object being to fill up all irregularities in the floor and make the surface level or smooth, the joints whether filled with plaster of 70 Paris or putty or the like, being sandpapered if necessary. The flour paste surface is an adherent to which plaster of Paris and some other substances will stick.

Around the edges of the floor there is 75 produced a relatively narrow band 4 of adhesive. A suitable type of paper is provided, say, relatively heavy Manila or building paper, which, however, may be replaced by other types of paper, cardboard, or the 80 like, and such paper is first prepared by dampening or wetting it and meeting edges are torn so as to produce a bevel. In the drawings, as best shown in Fig. 2, the paper is indicated with adjoining edges 6 torn to 85 a bevel and overlapping, thus producing a wide but smooth joint. In one type of floor covering two superposed layers 7, 8 of paper are provided and the showing of Fig. 2 may be taken as that of the layer 7, although the 90 layer 8 is substantially identical therewith so far as the joints are concerned. Whenever the joint 6 occurs in the paper layer 7 the overlapping edges forming the joint are united by a suitable adhesive, but before the 95 paper is laid upon the floor a thin strip of paper 9 is laid upon the plaster of Paris or other coating in position to underlie the joint in the paper 7, thus preventing the adhesive at the joint from sticking to the floor. 100 The paper layer 7 when laid upon the floor is secured to the floor by the strip 4 of adhesive placed about the edges and further by tacks 10 or other suitable fastening devices along the edges of the floor next to the 105 wall of the compartment where the floor covering is used. The tacks are employed to insure the holding of the paper at the edges next to the wall so that dependence is not had wholly upon the adhesive.

It is not necessary that the thin paper strip 9 be loose upon the floor except where

touching the strip 4 of adhesive, since this layer may be joined to the preliminary smooth coating 3 by lines of adhesive at the long edges, as indicated at 11 in Fig. 6, and then the upper surface of the strip 9 is covered with adhesive as indicated at 12, so that the paper layer 7 where a joint 6 occurs is united to the paper strip 9. This paper strip 9 may be laid in either direction across the flooring 1. The first layer 7 of paper is damp when placed in position and the second layer 8 is likewise damp but is laid crosswise or at right angles to the first layer, being united thereto by a layer 13 of a suitable adhesive. Experience has shown that the relatively long and narrow strips of paper change in width under changing weather conditions, becoming wider when damp and narrower when dry, without material variations in length, wherefore the crossing of the layers counteracts any shrinkage or expansion which might occur under changing weather conditions. The layers dry taut and then the paper layers are saturated with an oil such as linseed oil put on so heavy that it will substantially penetrate the whole, wherefore dampness will have no effect. The oil also makes the floor covering stronger and harder. When the oil is dried the floor is ready for painting, two coats 14 and 15 of paint being indicated in Fig. 1. For some purposes the floor described gives excellent results as has been demonstrated by long continued tests.

It takes considerable time for the oil and paint layers to thoroughly dry, so that time may be saved and a more durable floor covering provided by preparing an additional paper layer 16 made up of strips secured together as before with smooth overlapping joints 6 corresponding to the layers 7 and 8 first applied to the floor. This third layer can be prepared in a shop where a diagram of the floor to be covered may be laid out and the additional or supplementary paper layer may be prepared in the same manner as described with respect to the floor itself, except that no smoothing or filling coating is needed. After the supplementary layer or covering has dried it is saturated with oil or varnish and painted or otherwise ornamented, which ornamentation may, if desired, simulate tile or parquet or other design, as indicated at 17, and is then given a final coat of varnish. When dried it is removed from the shop floor and may be rolled up for shipment or storage until needed. In preparing the supplementary coating care is taken that the joints in the paper layer of which it is composed shall be at right angles to the top layer already placed upon the floor to be covered, it being desirable that at least two paper layers be placed upon the floor to be covered before

the supplementary layer or covering is applied, and furthermore the primary floor covering is oiled and has one coat of paint or the like applied thereto before the supplementary coating is placed in position. 70 The supplementary coating is then pasted down solid upon the primary coating, the prepared surface to receive the secondary coating being indicated at 18 in Fig. 3, and then one or more coats of varnish are applied to the supplementary or secondary floor covering. 75

With such a flooring long tests have shown that varnish or paints will last three or four times as long as though applied directly to a wooden or other floor, considering both as being exposed to the same amount of wear. For this reason a floor prepared as herein described may be very cheaply kept in repair. The decorative and protective coating of varnish or paint wears so much better on paper than on wood because the paper is softer and more pliable than the wood. 85

Floors that are exposed to hard wear may have an additional top finish applied thereto, the under layers being the same as before either as shown in Fig. 1 or Fig. 3, the latter showing being simply that of more layers of paper than in Fig. 1. For this purpose very heavy fiber is first placed in a bath of linseed oil or varnish so as to become thoroughly impregnated therewith and this oil or varnish may be either hot or cold, the heated oil or varnish penetrating the fiber better and faster than when cold. The fiber can be cut into any desired shape to imitate tile or other flooring and when the impregnating oil or varnish is dried the fiber is glued or cemented to the top layer of the floor covering. Such a fiber wear-surface is indicated at 19 in Fig. 4 and may be either scored to imitate tiling or may be actually cut up into blocks of various shapes. The wear coating 19 which is usually given a coat of oil or varnish after being laid is particularly desirable for kitchens, halls and public buildings as it produces a very durable and attractive looking flooring and will last for a long time 110 without any treatment at all. 115

Again, it is not absolutely necessary to plaster or putty or otherwise treat a rough or uneven floor to render it smooth for it can sometimes be covered with felt paper indicated at 20 in Fig. 5, although this does not preclude the application of the felt paper to the plaster or similar layer of Fig. 1 and other figures. The felt paper has the advantage of rendering the floor covering 125 more pliable than one where it is omitted and the floor covering is found to wear better.

While the primary and secondary layers are indicated as together containing but 120

three layers of paper, it will be understood that more layers may be used, as desired.

While in the foregoing description reference is made to floors only, it is to be understood that many of the features of the invention are applicable to inside and outside walls and roofs, and therefore the expression floor or the like as used in the claims is to be interpreted broadly enough to cover any surface or structure to which the invention is applicable.

What is claimed is:—

1. The combination with a floor or the like, of a covering therefor consisting of a plurality of superposed paper layers cemented together and connected at the edge portions to the floor or the like, and a smoothing or leveling layer of suitable material between the under paper layer and the floor or the like, the under layer of paper being free from union with the last-named layer except at the marginal portions.

2. The combination with a floor or the like, of a covering therefor consisting of a plurality of superposed paper layers cemented together and connected at the edge portions to the floor or the like, and a smoothing or leveling layer of suitable material between the under paper layer and the floor or the like, the under layer of paper being free from union with the last-named layer except at the marginal portions, and the paper layers being under contractual tension.

3. The combination with a floor or the like, of a covering therefor consisting of a plurality of superposed paper layers cemented together and connected at the edge portions to the floor or the like, and a smoothing or leveling layer of suitable material between the under paper layer and the floor or the like, the under layer of paper being free from union with the last-named layer except at the marginal portions, and said paper layers being impregnated with moisture repellent material.

4. A covering for a floor or the like, comprising a plurality of layers of paper united together and secured to the floor or the like under contractual tension, said layers of paper being impregnated with moisture repellent material, and a wear-surface applied to the covering.

5. The combination with a floor or the like, of a smoothing or leveling layer of suitable material applied directly to the floor or the like, a plurality of layers of paper cemented together and applied to the first-named layer with the marginal portions of the paper fastened to the floor or the like, and the paper layers under contractual tension, and a protecting surfacing for the paper layers.

6. The combination with a floor or the

like, of a primary covering composed of a plurality of united layers of paper, a smoothing or leveling layer of suitable material interposed between the paper layers and the floor or the like, said paper layers being secured at the margins to the floor or the like and laid under contractual tension, and a secondary or supplementary covering on and united to the primary covering.

7. The combination with a floor or the like, of a primary covering composed of a plurality of layers of paper each made up of sheets of paper having the meeting edges beveled and overlapping and cemented together, the layers of paper being also cemented together, a secondary or wear surface applied to the primary covering and a smoothing or leveling layer of suitable material separating the primary covering from the floor or the like.

8. The combination with a floor or the like, of a primary covering composed of a plurality of layers of paper each made up of sheets of paper having the meeting edges beveled and overlapping and cemented together, the layers of paper being also cemented together, a secondary or wear-surface applied to the primary covering, and a smoothing or leveling layer of suitable material separating the primary covering from the floor or the like, the paper layers being impregnated with water repellent material and the primary covering being united at the margins to the floor or the like and also being under contractual tension.

9. The combination with a floor or the like, of a sizing applied thereto, a smoothing layer of suitable material applied to the sizing, a plurality of layers of paper superposed upon the smoothing layer and united to the floor or the like at the margins, water repellent material impregnating the paper layers, and a wear surfacing superposed upon the paper layers.

10. The combination with a floor or the like, of a sizing applied thereto, a smoothing layer of suitable material applied to the sizing, a plurality of layers of paper superposed upon the smoothing layer and united to the floor or the like at the margins, water repellent material impregnating the paper layers, and a wear surfacing superposed upon the paper layers, said wear surfacing comprising a layer of paper impregnated with moisture repellent material and cemented to the primary floor covering and in turn provided with a surfacing of wear resistant material.

11. The combination with a floor or the like, of a primary covering consisting of layers of paper cemented together and united at the margins to the floor or the like with an intermediate layer of yieldable material between the paper layers and the floor.

or the like, moisture repellent material impregnating the paper layers, and a wear resistant surfacing applied to the primary covering.

- 5 12. The combination with a floor or the like, of a primary covering therefor composed of a plurality of layers of paper cemented together and secured at the margins to the floor or the like with an interposed 10 smoothing or leveling layer of suitable material between the floor or the like and the primary covering, said paper layers being impregnated with water repellent material, and a secondary layer of fiber impregnated 15 with water repellent material and cemented to the primary coating.
13. The combination with a floor or the like, of a primary covering therefor composed of a plurality of layers of paper cemented together and secured at the margins to the floor or the like with an interposed 20 smoothing or leveling layer of suitable material between the floor or the like and the primary covering, said paper layers being 25 impregnated with water repellent material, and a secondary layer of fiber impregnated

with water repellent material and cemented to the primary coating, said secondary covering being provided with a surfacing of wear resistant material.

14. The combination with a floor or the like, of a covering therefor composed of a plurality of layers of paper united together with each layer formed of strips of paper having the meeting edges beveled and overlapping and 30 there cemented, the joints of one layer of the paper running in a direction substantially perpendicular to the joints of the next layer of paper, and a strip underlying each joint of the under layer of paper, said strip being 35 united at the opposite edges to the floor or the like and the under layer of paper at the corresponding joint being there united to the underlying strip between the edges of the latter.

In testimony, that I claim the foregoing as my own, I have hereto affixed my signature in the presence of two witnesses.

PETTER C. N. PEDERSON.
